United States Patent Office

Des. 201,790
Patented Aug. 3, 1965

201,790

FLOOR WAXING MACHINE

Olin C. Hershberger and Chester B. Derr, Thompson, Conn., assignors to Astro Inc., Thompson, Conn., a corporation of Connecticut

Filed May 15, 1964, Ser. No. 80,041

Term of patent 14 years

(Cl. D9—2)

FIG. 1

FIG. 2

FIG. 3

FIG. 1 is a top plan view of a floor waxing machine showing our new design;

FIG. 2 is a bottom plan view thereof, and

FIG. 3 is a side elevational view thereof.

The side not shown has substantially the same appearance as the side shown.

We claim:

The ornamental design for a floor waxing machine, as shown and described.
